(57) **CLAIM**

The ornamental design for an irrigation apparatus handle, as shown and described.

DESCRIPTION

FIG. 1 is an illustrative top plan view of an irrigation apparatus handle showing our new design;

FIG. 2 is a bottom plan view thereof;

FIG. 3 is a side elevational view thereof;

FIG. 4 is an opposite side elevational view of the irrigation apparatus handle of FIG. 3;

FIG. 5 is front, side, and bottom perspective view thereof; and,

FIG. 6 is a rear, side, and top perspective view thereof.

The broken lines showing of the irrigation apparatus is for illustrative purposes only and forms no part of the claimed design.
